Ernest W. Robbins.

UNITED STATES PATENT OFFICE.

ERNEST W. ROBBINS, OF TOWNSHIP ONE, FRANKLIN COUNTY, NEBRASKA.

ATTACHMENT FOR COUPLING A PUMP TO A WINDMILL.

1,223,833.

Specification of Letters Patent. Patented Apr. 24, 1917.

Application filed February 26, 1915. Serial No. 10,808.

To all whom it may concern:

Be it known that I, ERNEST W. ROBBINS, a citizen of the United States, residing in the township of One, Franklin county, State of 5 Nebraska, have invented a new and useful Device or Attachment for Coupling a Pump to a Windmill.

The present invention has relation to improvements in pump couplers and analogous 10 devices; and as its general object it contemplates the provision of a novel device of this nature that includes a particularly formed spring or resilient agent to coöperate with the cam lever in order to afford facilities 15 for obtaining a quick connection and at the same time obviate premature breaking of parts.

Another object of my invention is to provide a device of the above character wherein 20 the particularly formed spring or resilient agent may be cheaply produced and which is constructed in order to afford facilities whereby the cam lever may be quickly and properly mounted in conjunction therewith.

25 A further object of my invention is to provide a device of the type in question that is extremely simple in construction, strong and durable, and highly practical from both the standpoint of the manufacturer and the 30 standpoint of the user; and which, it is believed, may be manufactured at a comparatively low cost.

Various other objects and advantages will 35 become apparent during the continuance of the following description.

These objects are accomplished by such means as are shown in their preferred form in the accompanying drawings, described in the following specification and then more 40 specifically pointed out in the appended claim.

In the accompanying drawings wherein like characters designate like parts throughout the several views:—

45 Figure 1 is a view in side elevation showing my invention as applied to a pump rod and wind mill drive member, and

Fig. 2 is a view in elevation also showing my invention in a like position.

50 In the present embodiment, I have shown a wind mill drive member 10, of the usual construction, provided adjacent its lower end with opposed wear plates 11 and 12 respectively, while fastening members such as

shown at 13 are passed laterally through the 55 plates and the drive member in order to retain the former in proper position. Wear plate 11 carries a suitably positioned guide 14 for reception of a pump rod 15, while the guide is in turn provided with a trans- 60 verse aperture or way 16 intersecting the longitudinal bore thereof and designed to receive a holding pawl hereinafter described. The pump rod 15 may be provided throughout its extent with suitably spaced openings 65 17 to receive the holding pawl or stud of guide 14, whereby it may be retained in certain adjusted positions with respect to the drive member 10.

Resilient agent 18, exemplified in the present embodiment by a metallic spring, has one end portion affixed to drive member 10 as at 19 while its opposite end portion 20 is twisted 90° in order to afford facilities 70 for the proper mounting of the cam lever 75 (subsequently described) and to serve other functions hereinafter appearing. By reason of the curvature of the end portion 20 of the spring, it will be noted that the intermediate portion thereof will be held out of 80 engagement with the respective fastening members 13 of the drive member 10 whereby the holding pawl or stud, presently referred to, may be securely held in a locking position by the spring. The bent portion 20 85 of the spring may be slightly curved as indicated at 21 in order to prevent engagement with the adjacent fastening member 13 when the spring is in a locking position.

Spring 18 further carries a holding pawl 90 or stud 22 as at 23, the said holding pawl or stud operating in the intersecting way 16 of guide 14 and designed to be passed through certain of the openings 17 of the pump rod in order to retain the latter in 95 certain adjusted positions with respect to drive member 10. In other words when the parts are in the position shown in full lines in Fig. 1, holding pawl 22 will be passed through the adjacent one of the openings 17 100 of the pump rod thereby retaining the latter in rigid relation to drive member 10.

Cam actuating lever 24 may be mounted on the bent portion 20 of spring 18 as at 25, for engagement with wear plate 12. Therefore it will be noted that upon proper manipulation of cam lever 24, the spring 18 105 may be moved so as to draw holding pawl

or stud 22 out of a locking position and permit of adjustment of the pump rod with respect to drive member 10.

The operation of my invention is substantially as follows:—

Spring 18 through its own tension normally retains holding pawl or stud 22 in a locking position so as to effect a rigid coupling between pump rod 15 and drive member 10. When desiring to release pump rod 15 for the purpose of effecting adjustment or otherwise, cam lever 24 may be moved to the position shown in dotted lines in Fig. 1 thereby forcing the free end of spring 18 outwardly with respect to drive member 10 and withdrawing holding pawl or stud 22 from a locking position with respect to pump rod 15. Again, upon movement of cam lever 24 to its initial position, holding pawl or stud 22 will be automatically moved to a locking position through the instrumentality of spring 18.

As hereinbefore stated, the bent portion 20 of spring 18 performs a dual function, namely, serving to retain the intermediate portion of spring 18 in spaced relation to drive member 10 and to afford facilities for the proper mounting of cam lever 24. Pivot member 25 may be so placed with respect to bent portion 20 that premature breaking of both the bent portion and the pivot member is precluded. In other words, detachable or permanently fixed bearings are eliminated and the spring 18 itself is rendered capable of properly carrying cam lever 24. The particular features of the bent portion 20 are especially important.

From the foregoing, it is believed that the advantages and novel features of my invention will be readily understood and therefore further detail description is deemed unnecessary.

Copies of this patent may be obtained for five cents each, by addressing the "Commissioner of Patents, Washington, D. C."

In reducing my invention to practice, I find that the form referred to herein as the most practical and preferred embodiment is the most efficient, but realizing that certain conditions will necessarily vary in concurrence with the adoption of my device, I desire to emphasize the fact that various minor changes in the details of construction and in the proportion of parts may be resorted to when required without sacrificing any of the advantages of my invention, as defined in the appended claim.

Having thus fully described my invention, what I claim as new and desire to secure by Letters Patent is:—

In a coupling device of the character described, the combination with a pump rod having a series of spaced openings and a member coupled therewith, a guide carried by said member to slidably receive said pump rod and having an opening to register with a selected one of said openings, and a wear plate opposite said guide, of a spring affixed at one end to said member and turned ninety degrees adjacent its other end to provide a bearing portion, a cam lever having its pivot member journaled through said bearing portion, and a retaining stud carried at a fixed point on said spring to operate in the way of said guide and enter a selected one of said orifices to retain said pump rod and said member in rigid relation, said cam lever engaging on said wear plate, whereby upon manipulation of said cam lever, said retaining stud may be moved to release said pump rod, substantially as described.

ERNEST W. ROBBINS.
